COLLAPSIBLE BOX HAVING INTERLOCKING END WALLS

Lawrence G. Trickett, Jr., Kansas City, Kans., and Clark O. Deemy, Kansas City, Mo., assignors to Crock-Paper Box Company, North Kansas City, Mo., a corporation of Missouri

Application April 11, 1949, Serial No. 86,764

2 Claims. (Cl. 229—35)

1.

This invention relates to boxes and particularly to those made from cardboard and like flexible material, the primary object being to provide a box that is readily assembled from an initially flat blank with the end walls thereof held in place by interlocking a plurality of flaps forming such end walls.

The collapsible box forming the subject matter hereof has been particularly designed for use by fruit and vegetable wholesale houses and more specifically as a container for bananas.

It is the usual present practice for wholesalers to deliver bananas in open top, rigid boxes that are retained by the retailer and held for pick up by the wholesaler at a later date. Inasmuch as such strong boxes are expensive to manufacture and therefore, valuable to the wholesaler, such pick up operation is necessary and in order to assure re-delivery, the wholesaler usually requires a deposit to be made by the retailer.

Accordingly, it is the most important object of the present invention to provide an inexpensive, open top box that may be used as a liner for the presently used rigid boxes and while the box of the present invention may be easily returned to the wholesaler, no deposit will be necessary because destruction thereof will not result in a substantial loss to the wholesaler.

Another important object of the present invention is the provision of a box having a pair of end walls formed by integral flaps on the bottom and side walls of the box disposed in overlapping relationship and provided with interlocking means capable of holding the flaps together.

Another object of the present invention is to provide a box of the above mentioned character wherein certain of the flaps forming the end walls of the box are provided with registering opening for receiving a tab that is formed to permit limited, relative sliding movement between the flaps, whereby the side walls of the box assume the contour of the rigid container within which it is to be used.

Other objects of the present invention relate to the way in which an interlocking means is provided for the end walls of a box, to, at the same time, present hand openings; the manner in which the interlocking tab is formed with converging edges to present a wedging action; and the manner of stamping the aforesaid tab from one of the flaps of the end walls having a dimension that will prevent separation of all of the flaps of the end walls.

Other objects will be made clear or become

apparent as the following specification progresses, reference being had to the accompanying drawing, wherein:

Fig. 1 is a top perspective view of a collapsible box having interlocking end walls made in accordance with our present invention.

Fig. 2 is a perspective view showing the box in a partially assembled condition.

Fig. 3 is a longitudinal, cross-sectional view taken on line III—III of Fig. 1.

Fig. 4 is a transverse, cross-sectional view taken on line IV—IV of Fig. 1; and

Fig. 5 is a plan view of the blank from which the box is made.

In Fig. 5, there is shown an initially flat blank 10 made from cardboard or the like, having a pair of spaced-apart longitudinal parallel lines of bend 12 and 14 and a pair of spaced apart parallel transverse lines of fold 16 and 18.

The lines of bend 12 and 14 are intersected by the lines of fold 16 and 18 to present a rectangular bottom wall 20 and a pair of side walls 22 and 24. The ends 26 and 28 of the box constitute the areas extending outwardly from the lines of fold 16 and 18 respectively. These ends 26 and 28 are further sub-divided into three flaps 30, 32 and 34. Thus, the side wall 22 has a pair of end flaps 30; the bottom wall 20 is provided with a pair of end flaps 32 and the side wall 24 is provided with a pair of end flaps 34.

In both ends 26 and 28, the flap 32 is separated from the flaps 30 and 34 by a pair of slits 36 and 38, the slits 36 being continuations of and aligned with the line of bend 12. Similarly, the slits 38 between flaps 32 and 34, are continuations of the line of bend 14. The two flaps 30 as well as the two flaps 34, forming end walls 26 and 28 respectively, are each provided with a trapezoidal opening 40 of identical size and shape. All of the openings 40 have a pair of parallel edges 42 and 44, all of which are substantially parallel with the longitudinal edges of the blank 10 and with the two lines of bend 12 and 14, as well as their corresponding slits 36 and 38 respectively.

The openings 40 are also provided with a pair of end edges 46 and 48 that converge as the shorter longitudinal edge 42 is approached.

It is to be noted that the openings 40 formed in the flaps 30 have their longer longitudinal edges 44 next adjacent the slit 36 and that in the same fashion, the openings 40 in the flaps 44 have their longer longitudinal edges next adjacent the respective slit 38.

A similarly shaped trapezoidal opening 50 is

formed in each of the flaps 32 of end walls 26 and 28 respectively. The parallel, longitudinal edges of openings 50 however, are parallel with the lines of fold 16 and 18 and, therefore, perpendicular to the longitudinal edges 42 and 44 of the openings 40. When the openings 50 are stamped in the flaps, the box material that is stamped therefrom is not entirely removed and accordingly, not severed along the shorter, longitudinal edge presenting a flap 52.

The two flaps 52 are identical and are accordingly provided with a longitudinal edge 54, a line of bend 56 in opposed relationship to the edge 54 and parallel thereto, and a pair of end edges 58 and 60.

The edge 54 of the tab 52 is next adjacent the respective line of fold 16 or 18 as the case may be, and is appreciably longer than the line of fold 56. The two edges 58 and 60 converge as the line of bend 56 is approached. For reasons that will hereinafter appear, the distance between the edge 54 and the line of bend 56 of tabs 52, is greater than the distance between the longitudinal edges 42 and 44 of the openings 40, but, the angularity of the edges 58 and 60 of tabs 52, is substantially the same as the angularity of the edges 46 and 48 of openings 40.

When the blank 10, shown in Fig. 5, is bent and formed into a completely assembled box 62, as illustrated in Fig. 1 of the drawings, the two side walls 22 and 24 are bent upwardly with respect to the bottom wall 20 on the lines of bend 12 and 14. The flaps 30 and the flaps 34, integral with side walls 22 and 24 respectively, are thereupon bent inwardly on lines of fold 16 and 18 as the case may be, with the flaps 30 and 34 of end wall 26 relatively overlapped and the flaps 30 and 34 of end wall 28 also in overlapped condition as clearly illustrated in Fig. 2 of the drawings.

The two flaps 32 integral with bottom wall 20 are thereupon bent upwardly upon lines of fold 16 and 18, as the case may be, and disposed in overlapping relationship with the proximal flap 30 or 34. When the side walls 22 and 24 are relatively parallel, and perpendicular to the bottom wall 20, and when the flaps 30 and 34 of each of the end walls 26 and 28 are in overlapped face to face relationship, the openings 40 thereof will be in registering alignment.

The inwardly bent tabs 52 are thereupon extended through the aligned openings 40 and the box 62 is permitted to assume the position shown in Fig. 1. The two side walls 22 and 24 will spread outwardly and converge as the bottom 20 is approached, but such outward spreading movement of the side walls 22 and 24, will be limited by the tabs 52 within the corresponding registering openings 40 in flaps 30 and 34 as the case may be.

It is seen that the three flaps 30, 32 and 34 of each of the end walls 26 and 28, will be effectively interlocked and because of the particular shape of the tabs 52, as well as the openings 40, the wedging action will take place. In other words, as shown in Fig. 4, one of the inclined edges 58 or 60 of the tabs 52, will tend to force the innermost flap 30 or 34 against the proximal face of the next adjacent flap 30 or 34 will also force the centermost of the three flaps of the end walls 26 or 28, against the innermost face of the flap 32. The greater the tendency of the side walls 22 and 24 to swing outwardly on their lines of bend 12 or 14, the greater will be the binding action caused by the tabs 52 in forcing the three flaps 30, 32 and 34 tightly together. Because of the inclined edges 46 and 48 of the open-

ings 40, the tabs 52 will assume a position adjacent the longer longitudinal edge 44 of the openings 40 in the manner illustrated in Fig. 4. Merely extending the tabs 52 through the aligned openings 40, as illustrated at the left in Fig. 3, is sufficient to hold the three flaps 30, 32 and 34 of the end walls 26 and 28 in the interlocked position. However, the openings 40 in the end walls, together with the openings 50, all of which will be in alignment, serve as a hand opening to permit carrying of the box 62. When the operator extends his hand inwardly through such aligned openings, he will most naturally cause the flap 52 to be bent upwardly as illustrated at the right end of the box as shown in Fig. 3.

Thus, the tabs 52 are formed into a loop with the flaps 30 and 34 disposed within the loops and between flap 52 and flap 32. The contents of box 62 will further serve in holding the tabs 52 in such looped condition.

It is seen from the foregoing that a collapsible box has been described that will readily assume the contour of the rigid container within which box 62 is to be disposed. Since it is desirable in packing fruits, particularly bananas, that the side walls of the box incline upwardly as the uppermost edges thereof are approached, the liner hereof will fulfill such need. When the liner is to be returned to the wholesaler, it is a simple matter to remove the tabs 52 from the aligned openings 40 and to return the entire box 62 to the flat condition as illustrated in Fig. 5 of the drawings, for ease of handling and simplification of storage. While, as above set forth, it is contemplated that the box forming the subject matter hereof, be used for handling bananas, and further that the same be used as a liner for another more rigid container, it is apparent that this box might well be used to contain other products and that the same may be utilized without the need of an outermost rigid container.

Furthermore, while the box 62 has been illustrated as having an open top, and a closed bottom wall 20, it is apparent that the same may be changed to include a top wall either integral with one or more of the side walls 22 or 24, or that the top be closed by a separate lid as is well known in this art.

It is apparent therefore, that many changes and modifications may be made in the box herein described without varying from the novel interlocking end wall construction that forms the subject matter hereof. It is desired therefore, to be limited only by the spirit of this invention as defined by the scope of the appended claims.

Having thus described the invention, what is claimed as new and desired to be secured by Letters Patent is:

1. In a box, a bottom wall; a pair of opposed side walls; and a pair of opposed end walls, each including a pair of overlapping inner flaps and an outer flap overlapping the inner flaps, there being a hinge connection for each side wall respectively joining the same integrally with the bottom wall, a hinge connection for each inner flap respectively joining the same integrally with a corresponding side wall, and a hinge connection for each outer flap respectively joining the same integrally with the bottom wall, each flap having a trapezoidal opening, each flap opening having a lowermost linear edge, a shorter uppermost linear edge, and a pair of linear side edges converging toward the uppermost edge, said edges forming the openings of the flaps, each of the outer flaps being provided with a trapezoidal tab

having a lowermost linear edge, a shorter uppermost linear edge, and a pair of linear side edges converging toward the uppermost edge of the tab, the uppermost edge of each tab being common to the uppermost edge of the opening of its outer flap and constituting a hinge connection integrally joining the tab with its outer flap, the tabs extending through the openings of the inner flaps and having their converging edges engaging the converging edges of the inner flaps whereby, as the side walls swing apart relative to the bottom wall, the inner flaps will be drawn tightly against their corresponding outer flaps.

2. In a box, a bottom wall; a pair of opposed side walls; and a pair of opposed end walls, each including a pair of overlapping side wall flaps and a bottom wall flap overlapping the side wall flaps, there being a hinge connection for each side wall respectively joining the same integrally with the bottom wall, a hinge connection for each side wall flap respectively joining the same integrally with a corresponding side wall, and a hinge connection for each bottom wall flap respectively joining the same integrally with the bottom wall, each flap having a trapezoidal opening, each flap opening having a lowermost linear edge, a shorter uppermost linear edge, and a pair of linear side edges converging toward the uppermost edge, said edges forming the open-

ings of the flaps, one of the flaps of each end wall being provided with a trapezoidal tab having a lowermost linear edge, a shorter uppermost linear edge, and a pair of linear side edges converging toward the uppermost edge of the tab, the uppermost edge of each tab being common to the uppermost edge of the opening of its flap and constituting a hinge connection integrally joining the tab with its flap, the tabs extending through the openings of proximal flaps and having their converging edges engaging the converging edges of the last-mentioned openings whereby, as the side walls swing apart relative to the bottom wall, the side wall flaps will be drawn tightly against their corresponding bottom wall flaps.

LAWRENCE G. TRICKETT, JR.
